(57) **CLAIM**

The ornamental design for a bottle, as shown and described.

DESCRIPTION

FIG. 1 is a perspective view of a bottle showing my new design;

FIG. 2 is a first side elevation view thereof;

FIG. 3 is a second side elevation view thereof;

FIG. 4 is a top elevation view thereof, with the opposing side details seen through the transparent surface not being shown for ease of illustration; and,

FIG. 5 is a bottom elevation view thereof, with the opposing side details seen through the transparent surface not being shown for ease of illustration.

The broken lines shown in the drawings are included for purposes of illustration only and form no part of the claimed design.
